UNITED STATES PATENT OFFICE.

ALONZO ALDRICH, OF BELOIT, WISCONSIN, ASSIGNOR TO BELOIT IRON WORKS, OF BELOIT, WISCONSIN.

MECHANISM FOR REELING PAPER AND THE LIKE.

Application filed December 15, 1923. Serial No. 680,819.

This invention relates to a mechanism for reeling paper and the like, and particularly to a mechanism and apparatus which is adapted to facilitate the winding of material on reels, the removal of full reels, and the positioning of empty reels to have material wound thereon.

In the manufacture of paper, it is particularly desirable that the reels be changed with a minimum of disturbance of the remainder of the machinery, and it is an important object of this invention to provide a mechanism for easily and effectively accomplishing this purpose with a minimum of wastage.

It is a further important object of this invention to provide a mechanism of the class described embracing power operated means for removing the empty reels into material receiving position and depositing the full reels on a supporting means from which they can be conveniently removed.

Another object of the invention resides in the provision of such a mechanism which is simple, durable and which may be easily operated.

Other and further important objects of this invention will be apparent from the disclosures in the specification and the accompanying drawings.

The invention (in a preferred form) is illustrated in the drawings and is herein-after more fully described.

On the drawings:

Figure 1 is a side elevation of a paper reeling mechanism embodying the principles of the present invention.

Figure 2 is an end elevation thereof.

Figure 3 is an enlarged fragmentary section on the line 3-3 of Figure 1 with parts in elevation.

Figure 4 is a fragmentary top plan view of the mechanism.

As shown on the drawings:

The mechanism of this invention is mounted upon suitably spaced upright frame members 1, and journaled in suitable bearings 2 on said frame members 1 is a shaft 3 which carries a rotatable material propelling drum 4. Said shaft 3 and drum 4 may be driven in a usual manner and from any suitable power source.

The upper sides of the frame members 1 are provided with outwardly extending

flanges 5 which afford supports for the reel supporting and changing mechanism which will now be described. Supported on the flange 5 at one end of the drum 4 is a U-shaped member 6 having an annular bearing flange 7 projecting inwardly therefrom to a point adjacent the end of the drum 4. Rotatably mounted on said bearing flange 7 is an annular reel supporting member 8, a flange portion 9 of which rotatably engages said bearing flange. A similar annular reel supporting member 8 is mounted at the other end of the drum 4 on a similar supporting means.

The annular reel supporting member 8 is provided with a plurality of pairs of spaced projections 10 and 11 which afford guideways for receiving trunnions 12 extending from the ends of suitable material receiving reels or winding drums 13. A web 14 of material such as paper which is to be wound on said reels 13 is passed over the drum 4 and propelled thereby, and is subsequently engaged around the reel 13 which is shown in dotted lines at position A in Figure 1. I have also indicated in dotted lines in Figure 1 a position A¹ which is approximately the point at which the cut-off end of the web of paper is first engaged around the reel 13, this being substantially the first point of contact of the reel with the drum 4.

It will be apparent that since the trunnions 12 are freely movable between the projections 10 and 11, that said reel and the material thereon will bear against the surface of the drum 4 and the web 14 of material to cause a rotation of the reel and the consequent winding of the material thereon.

The guideway afforded between the projections 10 and 11 permits movement of the axis of the reel toward or away from the axis of the drum 4 and it will be apparent that as material is wound on the reel in position A the axis thereof will move away from the axis of the drum 4.

A succeeding roll which is shown in waiting position B in Figure 1 is held in position between projecting members 10 and 11 positioned on the rotatable member 8 at approximately 90° from the similar members supporting the reel in receiving position A, and said reel is held away from the web of material 14 and the drum 4 by the engagement of the trunnions 12 thereof with suit-

able tables or stops 15 which are supported on the U-shaped member 6. At either end of the drum 4 means are provided for rotating the member 8 into position to discharge the reel or drum in position A when the same has sufficient material wound thereon, and for simultaneously moving the succeeding reel which was originally in waiting position B into starting position A¹ and then subsequently to receiving position A to receive the material as the web 14 passes over the drum 4.

Since the rotatable reel supporting member 8 is provided with pairs of projecting members 10 and 11 which may be spaced at approximately 90°, it will be apparent that when the succeeding reel 13 is moved into the position last mentioned, a succeeding pair of projecting members 10 and 11 will be moved into position B to receive an empty reel therebetween. The reel which is discharged from position A is received by supporting brackets 16, the outer faces of which are provided with receiving pockets 17 for the trunnions 12 of the discharged reel. It will be noted that the leading projecting members 11 are made somewhat longer than the following projecting members 10 in order to guide the trunnions 12 into the pockets 17.

The following projecting members 10 are formed outwardly at their outer ends as indicated at 10^a to facilitate the insertion of an empty reel between said projecting members and are made somewhat shorter in order to pass the discharged reel.

The mechanism for driving the rotatable reel supporting members 8 will now be described. Formed on the flange 9 is an external ring gear 18 which meshes with a gear 19 journaled on a stub shaft 20 projecting inwardly from the frame member 1. Said gear 19 in turn meshes with a pinion 21 mounted on a shaft 22 journaled between the frame members 1 and connected to a short shaft 23 mounted in a suitable bearing bracket 24 outside of the frame member 1, and having a helical pinion 25 secured to its outer end. Said helical pinion 25 meshes with a worm 26 which is mounted on the lower end of a diagonal shaft 27, the upper end of which is rotatably supported in a bracket 28 secured to the flange 5. Mounted on said shaft 27 above the bracket 28 is a bevel gear 29 which meshes with bevel gears 30 and 31 loosely mounted on the shaft 3. Said bevel gears are adapted to be selectively connected for rotation with said shaft 3 to drive the shaft 27 therefrom in either direction by means of a usual sliding clutch member 32 which is operated by a pivoted lever 33 supported on a suitable bracket 34 extending outwardly from the U-shaped member 6. The clutch member 32 is so constructed that it may be moved into the neu-

tral position shown in Figure 3 so that the rotation of the shaft 3 is not transmitted to the bevel gear 29 or shaft 27.

Driving means corresponding to the pinion 21, gear 19 and ring gear 18 are provided for the rotatable gear supporting member 8 at the other end of the drum 4 so that said reel supporting members may be simultaneously rotated from the shaft 3 in either direction when the clutch 32 is thrown into mesh with the bevel gears 30 or 31.

The function of the reversing mechanism is to allow the reel supporting members 8 to be rotated in the reverse direction when occasion arises. For example, if the web had just been started around the reel in position A' and a break occurred on the machine necessitating the removal of the material already on the reel, it would be simpler to reverse the reel supporting members until the reel was back in the position B, where the reel is out of contact with the drum and the material on the reel could be removed, than to revolve the reel supporting members in the forward direction until the succeeding reel came into the position B.

It will be apparent that when the reel in position A has had sufficient material wound thereon, it is only necessary to throw the clutch 32 into operative position to rotate the reel supporting members into position to discharge said full reel into supported position in the pockets 17 in the brackets 16, this rotation of the reel supporting members simultaneously acting to bring the empty reel from position B into position A' where the cut-off end of the web 14 may be engaged therearound, the web 14 being severed while the empty reel and full reel are both in contact with the contact drum 4. As soon as the web is safely started winding upon the empty reel, said reel is slowly moved from position A' to material receiving position A. During this movement of the reel from position A' to position A, the path of the reel axis is increasingly eccentric with respect to the drum axis due to the constantly increasing diameter of the reel as the web is wound thereon. The major portion of the winding operation occurs while the reel is in position A. When the empty reel from the position B is brought into position A, the succeeding pair of projections 10 and 11 will be brought into position B to receive a new empty reel 13 to be supported in said position until the new reel in position A has had sufficient material wound thereon.

It will of course be apparent that the number of pairs of projecting members 10-11 or the degree of spacing thereof may be varied as desired for accomplishing desired results with the reeling mechanism of this invention.

The apparatus of this invention is applicable for reeling all kinds of paper and is particularly adapted for use in connection with paper making machinery, but it should be borne in mind, of course, that this apparatus may be used for winding any appropriate material.

I am aware that many changes may be made, and numerous details of construction 10 may be varied through a wide range without departing from the principles of this invention, and I therefore do not purpose limiting the patent granted hereon otherwise than necessitated by the prior art.

15 I claim as my invention:

1. In a mechanism of the class described, a contact drum, a reel adapted to be propelled thereby and to receive material passing over said drum by co-action with said 20 drum, a rotatable support for said reel adapted to carry a plurality of similar reels in spaced relation, and power operated means for moving said support into position to discharge the full reel and to subsequently bring a fresh reel into material receiving position, the transfer of the material 25 onto the fresh reel being accomplished while both the fresh and full reels are in contact with the drum.

30 2. A reel support comprising a winding drum, a rotatable member, a plurality of oppositely positioned spaced projections thereon, an outwardly opening reel supporting guideway formed in each of said projections permitting the axis of a reel therein to be moved relative to said guideways towards or away from the axis of the rotatable member and into contact with said drum, and means for driving said rotatable member.

35 3. In a mechanism of the class described, a frame, material propelling means thereon, movable means outside of the propelling means for supporting a plurality of material receiving reels, means on the frame for supporting said last mentioned means, and means driven from the propelling means and extending inside the supporting means for operating the reel supporting means.

40 4. A reel support comprising a winding drum, a rotatable member, a plurality of spaced projections thereon, affording guideways for reel axes for coaction with said drum, a receiving bracket separately mounted, certain of said projections co-acting with said bracket to guide a reel clear of the rotatable member while the same is being

automatically discharged therefrom and from said drum.

5. In a mechanism of the class described, 60 a frame, a drum rotatably mounted thereon, rotatable means for supporting a plurality of reels eccentrically mounted relative to the drum, said reels being adapted to receive material for winding thereon by co-action with said drum, and means for driving said rotatable means to bring successive reels into contact with said drum, said material being severed between successive reels while said reels are both contacting said 70 drum.

6. In a mechanism of the class described, 75 a frame, a drum rotatably mounted thereon, a rotatable reel support mounted on said frame eccentrically of the axis of said drum and radial projections formed on said reel support forming guideways for receiving reels, the rotation of said support being adapted to cause an empty reel to come into contact with said drum, and subsequently to 80 cause a full reel to leave said drum due to the eccentricity of said support.

7. In a mechanism of the class described, 85 a contact drum, a web receiving reel adapted to wind up the web by coaction with said drum and means for guiding said reel during a portion of the winding process in a path eccentric with respect to the axis of said drum and of constantly increasing radius of curvature, the major portion of the 90 winding process taking place at the point of greatest eccentricity.

8. In a mechanism of the class described, 95 a contact drum, a web receiving reel adapted to wind up the web by coaction with said drum, and a rotatable member for guiding said reel during a portion of the winding process in a path eccentric with respect to the axis of said drum and of constantly increasing radius of curvature.

100 9. In a mechanism of the class described, a contact drum, a web receiving reel adapted to wind up the web by coaction with said drum, and a rotatable member eccentrically mounted with respect to said drum and having guiding and supporting means for said reel, the rotation of said member being effective to automatically discharge said reel at the point in its path of greatest eccentricity from said guiding means and 105 from coaction with said drum.

In testimony whereof I have hereunto subscribed my name.

ALONZO ALDRICH.
